UNITED STATES PATENT OFFICE

2,434,374

UNITARY REFRIGERATED CARBONATED BEVERAGE DISPENSING APPARATUS

Robert H. Tull, Springfield, Mass., assignor to Westinghouse Electric Corporation, East Pittsburgh, Pa., a corporation of Pennsylvania

Application June 1, 1943, Serial No. 489,264

13 Claims. (Cl. 62—141)

1

This invention relates to dispensing apparatus and particularly to apparatus for dispensing a cold, mixed carbonated beverage through a dispensing valve.

An object of the invention is to provide a relatively small, compact unitary container, within the confines of which are disposed chambers for cooling and carbonating the water component of a mixed beverage and for storing and cooling the syrup component of the same beverage.

The invention further contemplates the provision of a unitary, compact dispensing apparatus capable of supplying any one of a plurality of cold, mixed carbonated beverages as selected by the operator.

Still another object of the invention is to provide a compact unitary container provided with storage and carbonating chambers within its confines, together with a single refrigerant cooling element, also disposed within the container and adapted to cool the component parts of the beverage, the carbonating apparatus and the dispensing valve.

The invention also includes an improved means for carbonating water particularly adapted for use in a compact, unitary container of the type hereinafter described.

The invention further provides a compact, unitary cooling and dispensing container in which a single refrigerant cooling element is disposed or "sandwiched" between the liquid cooling chambers provided in the container, so that the refrigerating effect of the cooling element is used to the best advantage.

Another object is to provide a compact, unitary structural container having chambers for storing all the component parts of a cold, mixed beverage to be dispensed and for carbonating and cooling the water component of the beverage, which container also includes a single refrigerant cooling unit so disposed in the container that substantially all of its effective refrigerating surface is disposed in thermal contact with some of the walls of the aforesaid chambers.

Heretofore, drink dispensing machines have depended partly or entirely upon precooling a large reservoir of liquid at a relatively slow rate or upon instantaneous cooling of small quantities of liquid as it is dispensed. Apparatus made according to the present invention provides cooled storage capacity sufficient for peak load conditions and means for maintaining the water in the storage tank cool during the off-peak period. By combining the carbonator with the liquid cooler in a single, compact unitary container, there

2

is provided an assembly which may be refrigerated by a single refrigerating element disposed within the container. Heat losses which would be experienced with several separate units are avoided and a uniform temperature of all components of the beverage at the time of delivery is achieved.

These and other objects are effected by my invention as will be apparent from the following description and claims taken in connection with the accompanying drawings, forming a part of this application, in which:

Fig. 1 is a vertical section and elevation, partly diagrammatic, of the compact refrigerating and carbonating unit;

Fig. 2 is a horizontal section taken on the line II—II of Fig. 1; and

Fig. 3 is a horizontal section taken on the line III—III of Fig. 1.

20 The illustrated apparatus includes a cabinet 10 for housing the apparatus, the latter including a compact, unitary structural container A comprising a water-cooling and storage receptacle 11, a heat-absorbing unit or refrigerant evaporator 12 within the receptacle 11, and a carbonating, cooling, and storage receptacle 13 within the evaporator 12. A carbon dioxide expansion tube 14, which is open at the top, forms a gas expansion chamber within the receptacle 13; and a pipe 15 for uncarbonated water is positioned within the tube 14. The pipe 15 conducts water upward and discharges it over an umbrella-shaped spreader plate 16.

35 The unitary container assembly A thus is divided into a plurality of annular chambers surrounding the pipe 15, which in their order of arrangement from the pipe 15 outward comprise a gas expansion chamber 18 within the tube 14, a carbonating, cooling and storage chamber 19 within the receptacle 13, an evaporator chamber 20 within the cooling unit 12, and a liquid cooling and storage chamber 21 within the receptacle 11. The upper subchamber 22 of the outer chamber 21 is used for storing water and the lower part is preferably subdivided to form a plurality of storage chambers 23, 24, and 25 for other liquids such as syrups. The storage chambers 23, 24 and 25 are unnecessary if the water is to be dispensed without the addition of any other ingredient, such as flavoring or syrup. In Fig. 1, horizontal partitions 26 and 27 are shown as separating the chambers at different levels, and in Fig. 3, a vertical partition 28 is shown as separating the chambers 24 and 25 which are on the same

40 level.

45 The upper subchamber 22 of the outer chamber 21 is used for storing water and the lower part is preferably subdivided to form a plurality of storage chambers 23, 24, and 25 for other liquids such as syrups. The storage chambers 23, 24 and 25 are unnecessary if the water is to be dispensed without the addition of any other ingredient, such as flavoring or syrup. In Fig. 1, horizontal partitions 26 and 27 are shown as separating the chambers at different levels, and in Fig. 3, a vertical partition 28 is shown as separating the chambers 24 and 25 which are on the same

level. The entire container assembly A is enclosed by thermal insulation 31.

A pipe 32 supplies water to the top of the chamber 22. The water is supplied from a suitable source (not shown) through a pump 32a driven by a motor 32b which is started and stopped in response to the pressure in chamber 22, by a pressure-responsive switch 32c. Switch 32c is initially set so that the pressure in chamber 22 is always higher in that chamber than in carbonating chamber 19, thus ensuring the flow of water from storage chamber 22 to the carbonating chamber. The water flows down through staggered holes 33 in a plurality of flooded baffle plates 34 to prevent undue mixing of warmer water with colder water; and the colder water leaves by way of an outlet pipe 35 which connects with the pipe 15. The baffle plates 34, which are made of metal, are provided with apertures 34a at their central portions so that these plates fit snugly over the outer wall of the cylindrical evaporator unit 12. As these apertures are formed, an upturned flange 34b may be provided adjacent the apertures 34a to assist in centering the plates on the outer wall of the evaporator unit. The upturned flanges 34b may be metallically united to the outer evaporator wall as by welding or soldering so as to afford good thermal contact between the baffle plate 34 and the refrigerant unit 12. Thus it will be seen that the plates 34, in addition to serving as baffles for the incoming water, also act as fins or extended surfaces for conducting heat from the incoming water to the refrigerant evaporator or heat-absorbing unit 12.

A valve 36 controlled by a float 37 regulates the flow of water through the pipe 15 to maintain the level of carbonated water in the bottom of chamber 19 at the desired point. Carbonated water leaves the bottom of chamber 19 by way of an outlet pipe 40 and flows to a dispensing nozzle 41, a valve 42 being employed to control the flow.

Syrup is supplied to the syrup storage chambers 23, 24 and 25 through filling pipes 43 provided with sealing closure caps 44. Metallic baffle plates 45 are disposed in the upper syrup storage chamber 23, these plates being welded or soldered at their inner and outer edges to the adjacent tank walls and thus serving as fins or extended surfaces from the outer wall of cooling unit 12 to the interior of chamber 23. They are provided at their edges with staggered holes 46. Syrup leaves the tank 23 by way of an outlet pipe 47 and flows to the dispensing nozzle 41, a valve 48 being employed to control the flow. Syrup leaves the tank 24 by way of an outlet pipe 51 and flows to the dispensing nozzle 41, a valve 52 being employed to control the flow. Syrup leaves the tank 25 by way of an outlet pipe 53 and flows to the dispensing nozzle 41, a valve 54 being employed to control the flow.

The body 55 for the valves 42, 48, 52 and 54 is of heavy metal which is in physical contact with the walls of the evaporator 12, so that liquids flowing through the valves are maintained at low temperature up to the dispensing nozzle.

Liquid refrigerant is supplied to the bottom of the evaporator chamber 20 by a capillary tube 57, and gaseous refrigerant is removed from the top of the chamber by an outlet pipe 58. The refrigerant system illustrated includes a motor-compressor unit 59 and a condenser 60 operatively connected to the evaporator element 12. Operation of the refrigerant system is controlled

by a thermal-responsive element 62 in the bottom of the water cooling chamber 21. This controls the motor-compressor unit 59 through a pressure-operated snap-acting switch 63. Chilled water from the cooling chamber 22, which has been spread out at the top of the carbonating chamber 19, encounters expanding carbon dioxide gas issuing from the upper end of tube 14 and carbonation begins. Instead of supplying the gas to the top of the chamber, it may be supplied at the bottom of the chamber to flow upward against the flow of water. A plurality of alternately inclined metallic plates 65 have staggered openings 66 through which the liquid and carbon dioxide flow in passing down to the bottom of the tank. The openings are located in the higher edges of the plates whereby to form shallow pools of liquid which will readily absorb carbon dioxide. The openings are formed by striking out tabs 61 from metal plates. The edges of the plates are provided with bent flanges 68 by which they are spaced apart, the flanges being welded or soldered to the adjacent evaporator wall, if desired. They may be formed as spring elements which engage the tank walls frictionally. Alternate plates are alike. These plates 65 thus serve, as do the plates 34 and 45, as extended surfaces to conduct heat from the interior of carbonating chamber 19 to the inner wall of the cooling unit 12.

Carbon dioxide is supplied to the bottom of the expansion tube 14 by a supply pipe 70 leading from a pressure tank 71, one or more reducing valves 72 and pressure gauges 73 being provided in the line. Pressure for forcing syrup from the chambers 23, 24, 25 is provided by connecting supply pipes 74 from the tops of the chambers to the carbon dioxide supply line, a reducing valve 75 and a pressure gauge 76 being provided in the line.

A shelf 80 is provided beneath the dispensing nozzle 41 for cups 81, a drain pipe 82 being provided for removing any liquid which may spill.

In operation, the upper outer tank 22 is kept full of water which is to be carbonated. This water is cooled by the evaporator unit 12 and plates 34 to a predetermined temperature and the cooled water is drawn into the carbonator as required, as for example, to replenish that which has been dispensed. A considerable quantity of water is kept cooled at all times ready to be drawn as fast as drinks can be dispensed. The syrups in the lower containers are also cooled in storage as well as when being drawn for use.

The single refrigerant heat-absorbing unit 12 is in thermal heat-absorbing relationship with all of the liquid chambers, the carbonator, and the dispensing valve, as all of the aforesaid parts are made of metal, affording a compact, unitary heat-exchanging container.

The combination assembly hereby provided is very simple and compact; is very efficient and economical; and maintains very uniform temperature conditions for all of the components of the drink.

This application is, in part, a continuation of my earlier application Serial No. 470,751, filed December 31, 1942, which application has become abandoned.

While I have shown my invention in but one form, it will be obvious to those skilled in the art that it is not so limited, but is susceptible of various changes and modifications without departing from the spirit thereof, and I desire, therefore, that only such limitations shall be placed there-

upon as are specifically set forth in the appended claims.

What I claim is:

1. In apparatus for storing and dispensing a cold, mixed, carbonated beverage through a dispensing valve assembly, the combination of a unitary, structural container having partition means provided interiorly thereof for dividing the container into a chamber in which a syrup component is cooled, a chamber in which a water component is precooled, and a chamber in which the precooled water component is further cooled and carbonated, and a mechanical refrigerating system including a single refrigerant heat-absorbing unit disposed in one of said chambers and in thermal heat-absorbing relation with each of the other chambers, whereby to maintain said chambers and their contents at a temperature sufficiently low to produce a palatable mixed beverage.

2. In apparatus for storing and dispensing a cold, mixed, carbonated beverage through a dispensing valve assembly, the combination of a unitary, structural container having partition means provided interiorly thereof for dividing the container into a chamber in which a syrup component is cooled, a chamber in which a water component is precooled, and a chamber in which the precooled water component is further cooled and carbonated, and a mechanical refrigerating system including a refrigerant heat-absorbing unit disposed within the confines of said container for absorbing heat from all of said chambers, said heat-absorbing unit at least partially surrounding the walls of one of said chambers and being in heat exchange relation with the other of said chambers, with at least one of said other chambers surrounding said heat-absorbing unit.

3. In apparatus for storing and dispensing a cold, mixed, carbonated beverage through a dispensing valve assembly, the combination of a unitary, structural container having partition means provided interiorly thereof for dividing the container into a chamber in which a syrup component is cooled, a chamber in which a water component is precooled, and a chamber in which the precooled water component is further cooled and carbonated, and a mechanical refrigerating system including a refrigerant heat-absorbing unit disposed within the confines of said container, and out of contact with the external walls thereof, for absorbing heat from all of said chambers, said heat-absorbing unit at least partially surrounding the walls of one of said chambers and being in heat exchange relation with the other of said chambers, with at least one of said other chambers surrounding said heat-absorbing unit.

4. In apparatus for storing and dispensing a cold, mixed, carbonated beverage through a dispensing valve assembly, the combination of a unitary structural container, within the walls of which are disposed a water receptacle, a syrup receptacle and a carbonating receptacle, a mechanical refrigerating system including a refrigerant heat-absorbing unit having at least the major portion of its heat transfer surfaces disposed within the confines of the container, said heat-absorbing unit at least partially surrounding one of said receptacles and disposed between that receptacle and another of said receptacles, whereby to maintain all of said receptacles at a temperature sufficiently low to produce a palatable mixed beverage.

5. In apparatus for storing and dispensing a cold, mixed, carbonated beverage through a dis-

pensing valve assembly, the combination of a unitary structural container, partition walls inside the container for dividing it into a carbonating receptacle, a water receptacle and a syrup receptacle, said carbonating receptacle being entirely disposed in the container, said water receptacle surrounding the carbonating receptacle and being in thermal conducting relation with the syrup receptacle, a mechanical refrigerating system including a refrigerant heat-absorbing unit interposed between the water receptacle and the carbonating receptacle to absorb heat from both said receptacles and from the syrup receptacle, whereby to maintain all of said receptacles at a temperature sufficiently low to produce a palatable mixed beverage.

6. In apparatus for storing and dispensing a cold, mixed, carbonated beverage through a dispensing valve assembly, the combination of a unitary, structural container having partition means provided interiorly thereof for dividing the container into a chamber in which a syrup component is cooled, a chamber in which a water component is precooled, and a chamber in which the precooled water component is further cooled and carbonated, means for maintaining the pressure in the precooling chamber higher than that in the carbonating chamber, and a mechanical refrigerating system including a single refrigerant heat-absorbing unit disposed in one of said chambers and in thermal heat-absorbing relation with each of the other chambers, whereby to maintain said chambers and their contents at a temperature sufficiently low to produce a palatable mixed beverage.

7. In apparatus for dispensing a cold, carbonated beverage and for cooling and carbonating a component of the beverage, a unitary, heat-exchanging container having partition means for dividing the container into an inner carbonating chamber, an outer water-cooling chamber, and a refrigerant heat-absorbing unit disposed between the two aforesaid chambers, heat transfer plates disposed in thermal contact with the heat-absorbing unit and extending into the water-cooling chamber, other heat transfer plates also in thermal contact with the heat-absorbing unit and extending into the carbonating chamber, all of said plates presenting extended surfaces for absorbing heat from water flowing thereover, means for conveying cooled water from the outer cooling chamber to the carbonating chamber, a carbon dioxide gas inlet means to the carbonating chamber, and means for maintaining a predetermined liquid level in the carbonating chamber below the gas inlet thereto.

8. In apparatus for dispensing a cold, carbonated beverage and for cooling and carbonating a component part of the beverage, a unitary, structural container having partition means for dividing the container into an inner carbonating chamber, an outer water-cooling chamber, and a refrigerant heat-absorbing unit disposed between the two aforesaid chambers, heat transfer plates disposed in thermal contact with the heat-absorbing unit and extending into the water-cooling chamber, other heat transfer plates also in thermal contact with the heat-absorbing unit and extending into the carbonating chamber, all of said plates presenting extended surfaces for absorbing heat from water flowing thereover, means for supplying water to the upper part of the water-cooling chamber, means for conveying cooled water from the lower part of the water-cooling chamber to the upper part of the carbon-

ating chamber, a carbon dioxide gas inlet means to the carbonating chamber, and means for maintaining a predetermined liquid level in the carbonating chamber below the gas inlet thereto.

9. In apparatus for dispensing a cold, carbonated beverage through a dispensing valve, a unitary, structural container providing a heat exchanger, said container having partition walls for dividing the container into a centrally disposed chamber and a second chamber disposed about the central chamber, both of said chambers being adapted to retain water to be cooled, means provided in one of said chambers for carbonating the water therein, said container also having partition walls defining a chamber disposed outwardly of but adjacent to the central chamber for retaining syrup to be cooled, refrigerant heat-absorbing means disposed adjacent the periphery of the central chamber and in heat transfer relation with each of the other said chambers, and means for transferring cooled water from one of said water chambers to the other.

10. Refrigerating and carbonating apparatus comprising in combination, an annular carbonating container, an annular refrigerant container surrounding said carbonating container, an annular liquid cooling chamber surrounding said refrigerant container, said refrigerant container being in intimate heat-exchange relation with both the carbonating container and the liquid cooling chamber, thermal-conducting elements extending from the walls of said carbonating container and said liquid cooling chamber to the interior spaces thereof, a carbon dioxide inlet means to the carbonating chamber, and means for maintaining a predetermined liquid level in the carbonating chamber below the gas inlet thereto.

11. Refrigerating and carbonating apparatus comprising in combination, an interior carbon dioxide expansion tube which is open at the top and provided with means for supplying carbon dioxide at the bottom, a water supply pipe extending upward through said tube, means for spreading the water at the upper end of the supply pipe, walls defining a carbonating chamber surrounding said tube and supply pipe, walls defining separate storage chambers for water and flavoring surrounding said carbonating chamber, means for supplying water to the top of said water chamber, means for baffling the inflow of water at the top of said water chamber, and means for passing water from the bottom of said water storage chamber to the top of said carbonating chamber.

12. Refrigerating and carbonating apparatus comprising in combination, an interior carbonating chamber, an exterior liquid cooling chamber spaced from the carbonating chamber to form a refrigerant chamber therebetween, means for supplying refrigerant to and removing it from said refrigerant chamber, cooling plates secured in thermal contact with the outer wall of the refrigerant chamber and extending transversely of

the liquid cooling chamber, cooling plates secured in thermal contact with the inner wall of the refrigerant chamber and extending transversely of the carbonating chamber, said carbonating chamber plates being set at an inclination to retain a body of refrigerated carbonated liquid thereon, means for supplying liquid to said liquid cooling chamber, means for transferring refrigerated liquid from said water cooling chamber to the top of said carbonating chamber, means for supplying carbon dioxide to the top of said carbonating chamber, and means for withdrawing refrigerated carbonated liquid from the bottom of said carbonating chamber.

13. Refrigerating and carbonating apparatus comprising in combination, an interior carbonating chamber, an exterior liquid cooling chamber spaced from the carbonating chamber to form a refrigerant chamber therebetween, means for supplying refrigerant to and removing it from said refrigerant chamber, cooling plates secured in thermal contact with the outer wall of the refrigerant chamber and extending transversely of the liquid cooling chamber, cooling plates secured in thermal contact with the inner wall of the refrigerant chamber and extending transversely of the carbonating chamber, said carbonating chamber plates being set at an inclination to retain a body of refrigerated carbonated liquid thereon, means for supplying liquid to said liquid cooling chamber, means for transferring refrigerated liquid from said liquid cooling chamber to the top of said carbonating chamber, means for supplying carbon dioxide to said carbonating chamber, and means for withdrawing refrigerated carbonated liquid from the bottom of said carbonating chamber, said carbonating chamber plates being formed with angularly-bent edge flanges which engage the adjacent wall and which form abutting spacers between plates.
